UNITED STATES PATENT OFFICE.

CHARLES SCHAUFF, OF PORTLAND, OREGON.

RANGE-FINDING APPARATUS.

1,330,013.

Specification of Letters Patent.

Patented Feb. 3, 1920.

Application filed March 27, 1919. Serial No. 285,409.

To all whom it may concern:

Be it known that I, CHARLES SCHAUFF, a citizen of the United States, and resident of Portland, in the county of Multnomah and 5 State of Oregon, have invented a new and useful Range-Finding Apparatus, of which the following is a specification.

My invention relates to improvements in range finding apparatus in which the distance is ascertained by means of a right angle triangle, in which latter the length of one cathetus remains constant and is used 10 as base line, so that the variable angle may be read directly in terms of length for the other cathetus. In other words, this invention is based on the familiar trigonometrical formula— a equals b times tangent alpha—in which a is the cathetus from the stationary or central telescope to the object, 15 and b is the cathetus from the stationary to the movable telescope. A semi-circular railroad track is used to maintain a constant base b for the various possible triangles, so that angle alpha is readable directly in 20 miles for the distance a . If a gun is stationed at the apex of the right angle, pointing in the direction of said other cathetus, and equipped with a graduated scale for elevation according to distance, then the degrees of the variable angle need only be 25 transmitted to the gunner to give his gun the correct elevation for a direct hit.

The objects of my invention are to relieve the gun crew of all mathematical calculations, to save the Government the large expense incurred in target practice, and yet to be certain of hitting the desired object.

I attain these objects by the mechanism illustrated in the accompanying drawing, 40 in which Figure I is a diagrammatical plan view of the entire apparatus, and Fig. II is a diagrammatical side view of the cannon with some shell trajectories.

Similar numerals refer to similar parts 45 throughout the several views.

My apparatus may be used for frontier or coastal defense. Fig. I shows its application in the latter case. The cannon 1 may be one single piece of ordnance or a whole 50 battery of guns. As near as possible behind the gun is located a suitable observation tower, and on top of latter a telescope 2 with a graduated horizontal limb 3. From this instrument, which may be designated 55 as central station, base lines 4 and 5 extend parallel with the sea shore, one to the right

and one to the left. At the ends of said base lines are mounted telescopes 6 and 7 similar to the one at the central station, also mounted on suitable observation towers, but the 60 towers themselves are placed upon long and heavy railroad cars. These cars run on a railroad track 8 which extends rearward of the central station, and connects in a semi-circle the ends of the base lines 4 and 5. 65 Said track is divided into stations or degrees which should correspond with the degrees on the central telescope.

Any suitable long-distance method of communication, be it telephone, telegraph, 70 semaphore or wireless telegraphy, connects the central station 2 with the end stations 6 and 7. On the approach of an enemy ship 9 the central station 2 takes a sight and communicates the exact number of degrees 75 to the proper end station. The end station is quickly rolled into position, a sight is taken and the degrees of the angle are communicated either to the central station or directly to the gunners who have on their 80 gun 1 a pointer 10 and a vertical limb 11 with graduations to indicate the elevation of the gun for a direct hit.

The vertical limb 11 is attached to the aiming telescope 12 while the pointer 10 85 swings with the gun. This is done in order to make the same range finder applicable to mountainous countries, as will hereafter be explained.

It is advisable to have one instrument at 90 each end station, in order to be instantly ready whether the enemy approaches the central station from the right or from the left.

The proper graduation of the limb 11 on 95 the gun 1 has to be done on the proving ground, where a similar range finder is set up. A shot is fired and a permanent stake is set where the shot struck ground; a flag is placed on top of the stake (see flag 13 in 100 Fig. II); the aiming telescope 12 is then directed toward the stake and the vertical limb 11 is marked wherever the pointer 10 stands; now the telescope at the end of the base line 105 is directed toward the flag staff, or rather to the stake under the staff, and the number of degrees on the instrument is noted. This is continued until the whole distance is measured with shots and the corresponding degrees noted on gun and end telescope. These 110 data, having once been obtained, will hold good for every other gun of the same caliber,

providing the same base line, the same projectile, and the same projective force are employed.

Where the contour of a country necessitates the employment of a different base line, all that is necessary to do is, to measure off the new base line on the proving ground, direct the end telescope toward the flag staffs and note the variations in the different angles.

It has previously been noted that this gun may be used in mountainous countries. For this purpose the vertical limb 11 is attached to the aiming telescope 12 and, no matter how high or low the enemy might be located, the cannon 1 with its pointer 10 can always be set to a definite degree for a definite distance.

On an island or a peninsula, where it is not possible to have double base lines of sufficient length, one single base line may be employed. In that case both angle measuring telescopes at the ends of the base line are located on stationary towers and become central stations. A circular railroad track issues from each station, and separate movable telescopes are placed behind such stations. The dotted circle 14 issuing from station 2 indicates the railroad track, when

5 should be the only available base line and

telescope 7 becomes the central station for the track 14.

Lines 15 indicate the cathetus along which the firing is done.

Having described my invention, I claim: 35

1. In range finding apparatus, a telescope mounted for rotation about a fixed vertical axis, a semi-circular track having said axis at the center thereof, and a telescope slidably mounted on said track and having a 40 vertical axis about which it is independently rotatable.

2. In range finding apparatus, a telescope rotatable about a fixed vertical axis, a support therefor having a horizontal graduated 45 plate to indicate the azimuth movements of said telescope, a semi-circular track having said axis as its center and having stations corresponding to the graduations of said plate, a telescope rotatable about a vertical 50 axis and slidable bodily on said track, and means connected to the second telescope for indicating the distance of an object from the first named telescope when the lines of sight of both telescopes intersect on the object 55 and the straight line joining the two telescopes is at right angles to that joining such object and the first named telescope.

CHARLES SCHAUFL.
